UNITED STATES PATENT OFFICE.

ROBERT L. MILLER, OF SPOKANE, WASHINGTON.

VALVE MECHANISM FOR AUTOMATIC TRAIN-CONTROL APPARATUS.

1,424,420.

Specification of Letters Patent. Patented Aug. 1, 1922.

Application filed March 16, 1922. Serial No. 544,146.

To all whom it may concern:

Be it known that I, ROBERT L. MILLER, a citizen of the United States, and resident of Spokane, in the county of Spokane and State of Washington, have invented certain new and useful Improvements in Valve Mechanism for Automatic Train-Control Apparatus, of which the following is a specification.

10 My invention relates to valve mechanisms for automatic train control apparatus, and has particular reference to improvements in valve mechanism of the type disclosed in my copending application filed March 6, 15 1922 and serially numbered 541,552.

The broad purpose of my present invention is the same as the broad purpose of the mechanism disclosed in my prior application referred to, namely, to provide a valve 20 mechanism which will permit an engineer to set or release his brakes during such times as he is alert and properly observant of signals, but which will act, upon contact with ramp devices which preferably are operated 25 in conjunction with the usual signals, to cause an automatic application of his brakes in the event that he fails to observe or heed said signals.

In my prior application referred to I disclosed a rotatable valve operable when rotated to predetermined positions to control directly the flow of fluid in the train line, and I also disclosed a hollow ramp engageable shoe so arranged with respect to the 35 rotatable valve that if it became fractured or broken, air would exhaust from the train line with the result that the brakes would become automatically set, irrespective of whether the valve was or was not rotated. 40 A disadvantage of this prior valve mechanism, however, resides in the fact that if the shoe becomes broken air is not only exhausted from the train line, but from the source of fluid supply as well, and this latter 45 is the purpose of my present invention to avoid so that if the shoe becomes broken or fractured in use, air will be exhausted from the train line only and the supply will be automatically cut off.

50 My inventive idea is capable of embodiment in different mechanical constructions and arrangements, one of which is illustrated in the accompanying drawings, but it is to be understood that the structure shown 55 is merely intended as a disclosure of the

essential features and novel characteristics of my invention in a preferred form, and that various changes, modifications and desirable additions may be made in and to the same within its scope as defined in the appended claims.

In the drawings which are illustrative of features of novelty to be more fully described hereinafter, and wherein like characters of reference denote corresponding parts in the different views.

Figure 1 is an elevation of my improved valve mechanism showing the manner of connecting the same with the train line and supply pipes of the usual type of air brake system;

Figure 2, a central longitudinal section through my improved valve mechanism;

Figure 3, a transverse section on the line 3-3 of Figure 2;

Figure 4, an elevation of the projectile sleeve valve showing the fluid supply side thereof; and

Figure 5, a view similar to Figure 4 of the train line side of the sleeve valve.

Referring now to the drawings in detail, 10 designates a valve casing which is adapted to be suitably and permanently secured to a locomotive or other like vehicle, whereby certain movable elements of the mechanism are disposed for actuation by suitable ramp devices (not shown) located along the tracks. This valve casing is provided with a longitudinal bore 11 in which is rotatably mounted a plug valve 12 held in assembled 15 relation with the casing by a plate or cap 13 secured to one end of the casing by bolts 14. The bore 11 and the plug 12 preferably are tapered as shown whereby wear may be quickly and easily taken up by tightening 20 the bolts 14 as is apparent.

Formed in the plug 12 are two radial, circumferentially spaced passages 15 and 16 which are in communication with each other through the center of the plug and open 100 through the outer surface thereof, and one of them, 15, terminates in a channel 15' of limited length and which essentially extends circumferentially of the plug to one side of said passage only, but which may, if desired, 105 be extended in both directions therefrom as shown by the dotted lines in Figure 3 of the drawings. Also formed in the plug and communicating with the radial passages 15 and 16 is an axial passage 17 which is pref. 110

erably tapered and opens through one end of the plug and is closed at its other end as by means of the screw cap or plug 18.

Formed in opposite sides of the casing 10 are ports or passages 19 and 20 which open into the bore 11 and have communicating therewith, respectively, the train line pipe 21 and the fluid pressure pipe 22 of the usual type of air brake system, the latter pipe leading to the engineer's valve (not shown) whereby the pressure of fluid in the train line may be controlled for setting and releasing the brakes in the usual well known manner.

15 In the normal relation of the parts described in the foregoing and as shown in Figure 3 of the drawings, passage 15 is in communication with the train line and passage 16 is in communication with the fluid pressure pipe, and as said passages 15 and 16 are in relative communication, the fluid pressure pipe is normally in open communication with the train line pipe whereby the engineer may control the pressure of fluid in the train line to set and release his brakes in the ordinary manner. However, if plug 12 is rotated a predetermined amount in a predetermined direction to the right in Figure 3, passage 16 will become disaligned with 25 port or passage 20 and a solid portion of the plug will be moved into closing relation with said port or passage and thereby cut off communication between the fluid pressure supply pipe and the train line, while at the same time passage 16 will move into alignment with passage 24 in the casing 10 leading to the atmosphere, but passage 15 will remain in communication with the train line due to the circumferential channel 15'. 30 Thus, fluid pressure will be exhausted from the train line through passages 15, 16 and 24 and the brakes will become set, while control of the same will be removed from the engineer's hands except that he may exhaust fluid pressure by way of the by-pass pipe 25 and check valve 26 therein, which opens in the direction of the engineer's valve, to obtain an emergency application of the brakes. If desired, the circumferential channel 15' may be extended to both sides of the passage 15 as previously mentioned and a second port opening to atmosphere, shown by dotted lines at 27 in Figure 3 of the drawings, may be formed in the casing 10 in position to be aligned with said channel 15' when the plug is rotated in a reverse direction, to the left in Figure 3, so that under such conditions there will also be an exhaust of fluid from the train line. 55 60 The means for rotating the plug 12 consists of a shoe 28 connected to the plug and depending therefrom so as to be engageable with a ramp device, and which is adapted to be moved angularly to rotate the plug in one direction or the other, depending upon

whether the locomotive or other vehicle carrying the mechanism is proceeding ahead or backing up. This shoe is in construction a duplicate of the shoe disclosed in my co-pending application previously referred to 70 and includes a pipe 29 bent into U-shape and connected with the axial passage 17 whereby breakage or rupture thereof will result in loss of air from the train line with a consequent reduction of pressure and setting of 75 the brakes.

In connection with the structure so far described, it will be noted that if a break should occur in the pipe 29 while the shoe is in normal position, that is, vertical with the ports 15 and 16 establishing open communication between the fluid pressure pipe and the train line, exhaust of fluid would occur not only from the train line but from the fluid pressure pipe as well, which is undesirable and which is a disadvantage of my prior valve mechanism now eliminated by my present improvements consisting essentially of a hollow sleeve 30 disposed within the axial bore 17 of plug 12.

The bore 17 is tapered in the direction of its open end, that is, towards the end in communication with the pipe 29, and the sleeve 30 is also tapered and of a size to snugly fit said bore when moved towards the smaller end thereof. Normally, however, said sleeve is disposed in the larger portions of the bore and is retained therein by an expansion coil spring 31 arranged between the smaller end of the sleeve and the adjacent end of the bore 17 and which acts to hold the larger open end of the sleeve in contact with the cap or plug 18. A key 32 prevents rotation of the sleeve with respect to the plug 12 so that in the normal relation of parts a circular opening 33 in the side of the sleeve is maintained in alignment with the passage 16, while an elongated opening 34 in the opposite side of the sleeve is maintained in alignment with the passage 15. In the smaller end of the sleeve is formed a relatively small opening 35.

Now, when the shoe is disposed normally vertical, communication between the fluid pressure supply pipe and the train line is 115 had through passages 15 and 16 by way of the openings 32 and 33 in the hollow sleeve and the pipe 29 is subject to train line pressure by way of opening 35. Therefore, if the pipe 29 should break or become ruptured 120 in any manner, the air therein will exhaust to atmosphere thus reducing the pressure against the outer surface of the small end of the sleeve so that the same will be moved longitudinally within the bore 17 by the 125 greater pressure reacting from the cap or plug 18 against the inner face of its substantially closed small end and the sleeve consequently will be forced into snug engagement 130 with the bore 17, while at the same time open-

ing 33 will be disaligned from passage 16 thus cutting off the supply. Train line fluid may still exhaust, however, due to the fact that elongated opening 34 remains in alignment with passage 15. It is thus apparent that regardless of the angular disposition of the shoe, the fluid pressure supply will be cut off both from the train line and the shoe whenever the latter breaks, and when the break has been repaired it is equally apparent that as pressure equalizes on both sides of the sleeve the latter will automatically return to normal position under the influence of spring 31.

15 I claim:—

1. In automatic train control apparatus, a valve mechanism adapted to be located in the train line between the usual brake actuating means and the ordinary engineer's valve for automatically effecting a reduction in train line pressure, said mechanism including a rotatable valve directly operable to control the flow of fluid in the train line, an angularly movable shoe including a hollow member subject to train line pressure and operable to rotate said valve, and means operable in all angular positions of said shoe when fluid pressure is exhausted therefrom to automatically cut off communication between the fluid pressure pipe and the train line.

2. In automatic train control apparatus, a valve mechanism adapted to be located in the train line between the usual brake actuating means and the ordinary engineer's valve for automatically effecting a reduction in train line pressure, said mechanism including a rotatable valve directly operable to control the flow of fluid in the train line, an angularly movable shoe including a hollow member subject to train line pressure and operable to rotate said valve, and means operable in all angular positions of said shoe when fluid pressure is exhausted therefrom to automatically cut off communication between the fluid pressure pipe and the train line and between the fluid pressure pipe and said hollow member.

3. In automatic train control apparatus, a valve mechanism adapted to be located in the train line between the usual brake actuating means and the ordinary engineer's valve for automatically effecting a reduction in train line pressure, said mechanism including a rotatable valve directly operable to control the flow of fluid in the train line, an angularly movable shoe including a hollow member subject to train line pressure and operable to rotate said valve and means operable in all angular positions of said shoe when fluid pressure is exhausted therefrom to automatically cut off communication between the fluid pressure pipe and the train line and between the fluid pressure pipe and said hollow member.

4. In automatic train control apparatus,

a valve mechanism adapted to be located in the train line between the usual brake actuating means and the ordinary engineer's valve for automatically effecting a reduction in train line pressure, said mechanism including a rotatable valve directly operable to control the flow of fluid in the train line, an angularly movable shoe including a hollow member subject to train line pressure and operable to rotate said valve, and means carried by said rotatable valve and operable in all angular positions of said shoe when fluid pressure is exhausted therefrom to automatically cut off communication between the fluid pressure pipe and the train line and between the fluid pressure pipe and said hollow member.

5. In automatic train control apparatus, a valve mechanism adapted to be located in the train line between the usual brake actuating means and the ordinary engineer's valve for automatically effecting a reduction in train line pressure, said mechanism including a rotatable valve directly operable to control the flow of fluid in the train line, an angularly movable shoe including a hollow member subject to train line pressure and operable to rotate said valve, and projectile and retractable means carried by said rotatable valve and operable in all angular positions of said shoe when fluid pressure is exhausted therefrom to automatically cut off communication between the fluid pressure pipe and the train line and between the fluid pressure pipe and said hollow member.

6. In automatic train control apparatus, a valve mechanism adapted to be located in the train line between the usual brake actuating means and the ordinary engineer's valve for automatically effecting a reduction in train line pressure, said mechanism including a rotatable valve directly operable to control the flow of fluid in the train line, an angularly movable shoe including a hollow member subject to train line pressure and operable to rotate said valve, and projectile and retractable means carried by said rotatable valve and operable by the pressure of train line fluid in all angular positions of said shoe when fluid pressure is exhausted therefrom to automatically cut off communication between the fluid pressure pipe and the train line and between the fluid pressure pipe and said hollow member.

7. In automatic train control apparatus, a valve mechanism adapted to be located in the train line between the usual brake actuating means and the ordinary engineer's valve for automatically effecting a reduction in train line pressure, said mechanism including a rotatable valve directly operable to control the flow of fluid in the train line, an angularly movable shoe including a hollow member subject to train line pressure

and operable to rotate said valve, and a hollow sleeve arranged in said rotatable valve for automatically cutting off communication between the fluid pressure supply and said hollow member when fluid pressure is exhausted from the latter.

8. In automatic train control apparatus, a valve mechanism adapted to be located in the train line between the usual brake actuating means and the ordinary engineer's valve for automatically effecting a reduction in train line pressure, said mechanism including a rotatable valve directly operable to control the flow of fluid in the train line, an angularly movable shoe including a hollow member subject to train line pressure and operable to rotate said valve, and a hollow sleeve arranged in said rotatable valve for automatically cutting off communication between the fluid pressure supply and said hollow member when fluid pressure is exhausted from the latter, said hollow sleeve normally establishing communication between the fluid pressure supply pipe and the train line pipe and being movable under the influence of pressure in both of said pipes to cut off the aforesaid communication between the fluid pressure supply pipe and said hollow member.
- 25 9. In automatic train control apparatus, a valve mechanism adapted to be located in the train line between the usual brake actuating means and the ordinary engineer's valve for automatically effecting a reduction in train line pressure, said mechanism including a rotatable valve directly operable to control the flow of fluid in the train line, an angularly movable shoe including a hollow member subject to train line pressure and operable to rotate said valve, and a hollow sleeve arranged in said rotatable valve for automatically cutting off communication between the fluid pressure supply and said hollow member when fluid pressure is exhausted from the latter, a spring normally holding said sleeve in position establishing communication between the fluid pressure supply pipe and the train line pipe, and means whereby said sleeve is moved under the influence of train line pressure against said spring to cut off communication between the fluid pressure supply pipe and said hollow member when the pressure of fluid in the latter is reduced.

- 55 10. In automatic train control apparatus, a valve mechanism adapted to be located in the train line between the usual brake actuating means and the ordinary engineer's valve for automatically effecting a reduction in train line pressure, said mechanism including a rotatable valve directly operable to control the flow of fluid in the train line, an angularly movable shoe including a hollow

member subject to train line pressure and operable to rotate said valve, said rotatable valve having a tapered axial passage and a pair of axial passages therein, the radial passages normally communicating with the train line and the fluid pressure supply pipe, respectively, a hollow sleeve disposed in said axial passage and having an opening therein of substantially the same size as and normally communicating with the passage in the rotatable valve which is in communication with the fluid pressure supply pipe, said sleeve being further provided with an elongated opening at all times in communication with the passage in the rotatable valve which is in communication with the train line, means normally holding said sleeve with the aforementioned openings and passages in alinement, respectively, and means whereby said sleeve is moved under the influence of train line pressure to cut off communication between the fluid pressure supply pipe and said hollow member when the pressure of fluid in the latter is reduced.

11. In automatic train control apparatus, a valve mechanism adapted to be located in the train line between the usual brake actuating means and the ordinary engineer's valve for automatically effecting a reduction in train line pressure, said mechanism including a rotatable valve directly operable to control the flow of fluid in the train line, an angularly movable shoe including a hollow member subject to train line pressure and operable to rotate said valve, said rotatable valve having a tapered axial passage and a pair of axial passages therein, the radial passages normally communicating with the train line and the fluid pressure supply pipe, respectively, a hollow sleeve disposed in said axial passage and having an opening therein of substantially the same size as and normally communicating with the passage in the rotatable valve which is in communication with the fluid pressure supply pipe, said sleeve being further provided with an elongated opening at all times in communication with the passage in the rotatable valve which is in communication with the train line, means acting to prevent relative rotation of the sleeve and said rotatable valve, means normally holding said sleeve with the aforementioned openings and passages in alinement, respectively, and means whereby said sleeve is moved under the influence of train line pressure to cut off communication between the fluid pressure supply pipe and said hollow member when the pressure of fluid in the latter is reduced.

In testimony whereof I hereunto affix my signature.

ROBERT L. MILLER.
